UNITED STATES PATENT OFFICE.

JOHN PERRY DRAPER, OF PORT HURON, MICHIGAN.

PUZZLE TOY.

1,119,349.

Specification of Letters Patent.

Patented Dec. 1, 1914.

Application filed February 7, 1914. Serial No. 817,269.

To all whom it may concern:

Be it known that I, JOHN PERRY DRAPER, a citizen of the United States, residing at Port Huron, in the county of St. Clair and State of Michigan, have invented new and useful Improvements in Puzzle Toys, of which the following is a specification.

My invention relates to a puzzle toy and has as its principal object the provision of a normally closed device which contains a surprise of some character and the opening of which affords exercise for ingenuity.

A further object of my invention resides in the particular arrangement and combination of parts hereinafter described.

In the accompanying drawing:—Figure 1 is an elevational view of a device embodying my invention. Fig. 2 is an elevational view of the central portion of the device shown in Fig. 1, showing the same opened. Fig. 3 is a horizontal sectional view of a portion of the device shown in Fig. 1. Fig. 4 is a detail elevational view of an element used in fastening the doors of the device. Figs. 5, 6, and 7 are diagrammatic views showing the steps taken in the solution of the puzzle.

Throughout the separate views the same part is designated by the same reference character.

Referring more particularly to the drawing, 1 is a structure, one face of which is made to represent a miniature castle, said structure being provided with a central tower in which is a space or recess shown at 3 in Fig. 2. The space 3 is normally closed by doors 4—4 which are mounted on hinges 5—5. The space 3 is provided with a movable floor 6, the edge of which projects slightly beyond the doors when they are closed, as shown at 7. The movable floor piece 6 is provided with teeth 8—8 on its edges and the bottoms of the doors 4 carry gear wheels 9—9 which mesh with the teeth 8—8. It will be clearly seen from Fig. 3 that the arrangement is such that the doors 4—4 are held closed when the floor member 6 remains in the recess 3 but that the doors are opened as soon as the floor 6 is pulled out into the position shown in Fig. 3. It will be seen also that the movable floor 6 is slotted as shown at 10 and a pin 11 is provided which holds the same to the base

of the structure but which permits it to be slid back and forth in order to operate the doors. Carried by the movable floor 6 likewise is a figure 12 which I have shown as the figure of a woman carrying a banner on which is inscribed the legend "Votes for women" and the disclosure of which upon the opening of the doors operates as a surprise to the person who solves the problem of opening the doors 4.

As previously stated, the doors 4 are normally closed and for this purpose are provided with half rings such as 13—13 which project forwardly substantially at right angles to the face of the doors near the edges thereof as shown in Fig. 1. I provide also a removable plate 14 which is provided with a central aperture 15 adapted to fit over the rings 13 as shown in Fig. 1. On the structure 1 near the right hand side thereof I place a hook 16 and on the left hand side thereof I place two eyes such as 17 and a rope or cord is run through the eyes 17 and formed into a closed loop in which is engaged a ring 18 having a handle 19 attached thereto. The loop or cord 20 is then run through the rings 13 after the plate 14 has been placed over the rings and the loop is placed over the hook 16 at the right of the structure. The castle doors are now securely closed as indicated in Fig. 1 and the puzzle is to open the prison doors without taking the cord 20 from the hook 16.

The key to the puzzle is as follows:—Take hold of the upper length of the cord 20 by the finger and thumb of the right hand at the point marked "A" and pull it outward about an inch or so and hold it there. Then with the left finger and thumb take the lower length of the cord at the point "B." Pull the lower length out a little and carry it up, over that held in the right hand and place it on the hook 16, leaving it there but still holding the upper length of the cord by the right hand. Then take the cord by the left hand at the point marked "C," carry it slightly forward and up and over and place it also on the hook. Now let go of the cord with your right hand and take hold of the handle 19 and pull on the same, when you will find that the cord passes out of the rings in the door but still remains on the hook. Pull the cord forward and out of the

way of the doors, take down the bar 14 and pull out the floor piece 6 which projects under the doors and the same will swing outwardly.

5 Having thus described my invention, what I claim is:—

1. A puzzle toy comprising in combination, a prison, a pair of gates for said prison, rings projecting from the front of said gates, 10 a looped cord slidably attached to said prison and adapted to pass through said rings, and a hook for receiving one end of said loop.

2. A puzzle toy comprising in combination, a prison, a pair of gates for said prison, rings projecting from the front of said gates, 15 a looped cord slidably attached to said prison and adapted to pass through said

rings, a hook for receiving one end of said loop, and a handle secured to said loop at 20 the end opposite to said hook.

3. A puzzle toy comprising in combination, a prison, gates for said prison, rings projecting from the front of said gates, a bar having an aperture therein adapted to 25 fit over said rings, a loop slidably secured to said prison adapted to pass through said rings on the outside of said bar, and a hook adapted to receive one end of said loop.

In testimony whereof I affix my signature 30 in the presence of two witnesses.

JOHN PERRY DRAPER.
